CLAIM

An ornamental design for an applicator for applying artificial lash extensions, as shown and described.

DESCRIPTION

FIG. 1 is a perspective view of an applicator for applying artificial lash extensions;

FIG. 2 is a top side view thereof;

FIG. 3 is a bottom side view thereof;

FIG. 4 is a right side view thereof;

FIG. 5 is a left side view thereof;

FIG. 6 is a front side view thereof; and,

FIG. 7 is a back side view thereof.

The broken lines consisting of evenly spaced dashed lines in the drawings illustrate portions of the applicator for applying lash extensions that form no part of the claimed design. The broken lines consisting of long and short dashed lines in the drawings illustrate the boundary of the claimed design and it is understood that the claimed design extends to the boundary that forms no part of the claimed design.
